Samuel Willis
Letters Patent.

The Schedule referred to in these Letters Patent and making part of the same
containing a description in the words of the said Samuel Willis himself,
his improvement upon the Scales.

The general appearance both of the beam and pan is similar to those
in common use; but this peculiarity of weight is that the beam is
water. The main scale is placed which is nearest the mouth, and on
the beam and placed in a right line with it, and the other scales are placed
so that one edge of the main scales, and one edge of another scale are
in a right line with the bottom of the notch; in the corresponding edge
of the beam, and the other side is also constructed upon the same prin-
ciple which brings both sides to the principle of the Balance, and the sec-
ond and third scales are placed as usual, but the first or main scale
is so long as to let its edge play on the end scale, and the beam be-
ing correctly graduated cannot fail of giving the true weight.
